UNITED STATES PATENT OFFICE

RICHARD G. TURNER, OF WORCESTER, MASSACHUSETTS, ASSIGNOR TO CROMPTON & KNOWLES LOOM WORKS, OF WORCESTER, MASSACHUSETTS, A CORPORATION OF MASSACHUSETTS

SHUTTLE BOX FOR WEFT-REPLENISHING LOOMS

Application filed February 19, 1929. Serial No. 341,157.

This invention relates to a shuttle box for a loom using two or more shuttles and in which two or more boxes are provided at the weft replenishing side of the loom.

More specifically, my invention relates to looms of the type described, in which provision is made for transferring weft carriers by direct rearward and substantially horizontal movements.

It is the object of my invention to provide improvements in shuttle box construction by which the threading of the shuttles after transfer is facilitated and the mistreading or breaking of filling is greatly reduced.

My invention further relates to arrangements and combinations of parts which will be hereinafter described and more particularly pointed out in the appended claims.

A preferred form of the invention is shown in the drawings in which

Fig. 1 is a front elevation of my improved shuttle box construction;

Fig. 2 is a plan view thereof, partly in section, taken along the line 2—2 in Fig. 1;

Fig. 3 is an end view of the shuttle box, with certain parts omitted, and taken along the line 3—3 in Fig. 1; and

Fig. 4 is a sectional end elevation, taken along the line 4—4 in Fig. 1.

Referring to the drawings, I have shown a portion of a lay 10 mounted on the usual swords 11 and designed for use in a double shuttle loom. An upper shuttle box 20 and lower box 30 (Fig. 3) are provided in which pickers 21 and 31 (Fig. 1) are slideable under the impulse of a picker stick 31'.

Rigid frame members 40 extend upward at the rear of the lay 10, being preferably formed as continuations of a sheet metal frame or casing 41 enclosing the lay 10. A box member 42 is supported by the members 40 and a top frame member 43 is secured to the box member 42 by bolts 44, the member 43 projecting over the upper shuttle box 20.

A bottom plate 32 is secured to the lay by screws 33, which plate forms an extension of the shuttle race. A partition of separating member 45 extends between the shuttle boxes 20 and 30 and is held in position by bolts 46 extending vertically through the bottom

plate 32, back box plate members 50 and 52 (Fig. 1), the separating member 45, and the top frame member 42. The bolts 46 hold these several members in superposed position and rigidly disposed with reference to 55 each other.

At its front end, the separating member 45 is extended both upward and downward, as indicated at 54 and 55. These upward and downward extensions are greatly reduced in width in the middle portion of the box, as indicated at 56, to permit horizontal transfer of weft carriers to the shuttles contained in the boxes.

The right hand end portions of the parts 54 and 55 are inclined or beveled, as indicated at 57 and 58, to facilitate entrance of weft into the openings 59 above and below the separating member.

Back binders 60 are pivotally mounted in 70 the back box plates 50 and 52 and are provided with longitudinal openings 64, permitting rearward ejection of weft carriers from the shuttles. Binder springs 65 (Fig. 2) of the usual type are also provided.

Reference to Fig. 4 will indicate that the bottom plate 32 is inclined downward and rearward and that the separating partition 45 is inclined upward and rearward. The object of placing the parts 32 and 45 at downward and upward inclinations is for the accommodation of shuttles having their lower surfaces disposed at angles substantially corresponding to the plane of the warp in the upper and lower sheds at the time when the 85 shuttles are picked.

By thus forming the under faces of the shuttles at the angles of the sheds, all available space in the shed openings is utilized, either for increasing the weft capacity of 90 the shuttle or for increasing the thickness of the upper or lower walls of the shuttles, thereby increasing their strength and wearing qualities.

The extreme outer end portions of the separating member 45 are extended upward and downward, as indicated at 70, but to a somewhat less extent than at the inner end portions 54 and 55. The portions 70 are again cut away at 71 to permit the operation of a 100

shuttle feeler and said portions are then again extended upward and downward, as indicated at 72, to provide front guides for the pickers 21 and 31.

8 It is desirable that the pickers be separately adjustable, so that the upper and lower shuttles may each be boxed in the exact desired position. For this purpose, I provide a bracket 80 on the end of the lay 10, in which 70 adjustable stops 81 and 82 are threaded and adjustably secured. By adjusting the stops 81 and 82, the outer or boxed position of each shuttle may be established in an exact desired location.

15 As the front portions of the separating partition 45 are entirely supported by said separating partition and are entirely free at their upper and lower edges, the passing of a weft end over or under said separating 20 member is entirely unobstructed and there is much less probability of breakage than in the common construction where the weft end is drawn through the shuttle box after the shuttle. 25

25 I have thus provided an improved construction by which horizontal transfer of weft carriers and subsequent threading of the shuttles is greatly facilitated and also a construction in which the maximum available shuttle opening in the sheds is utilized. 90

Having thus described my invention and the advantages thereof, I do not wish to be limited to the details herein disclosed, otherwise than as set forth in the claims, but 95

35 what I claim is:—

1. In a fly shuttle loom, double shuttle boxes having a T-shaped separating member between said boxes entirely supported from the rear wall of said double shuttle boxes 100 and having upper and lower shuttle retaining projections at its front edge disposed in front of the upper and lower shuttles respectively and said boxes having unobstructed weft passages above and below said separating member at the front side of said boxes. 105

40 2. The combination in a loom as set forth in claim 1, in which said projections are reduced in width at the middle portion of their length to permit weft bobbin transfer there- 110 over and thereunder, the wider and narrower portions of said projections being connected by inclined portions.

45 3. In a double shuttle loom, a pair of superposed shuttle boxes in which the bottom 115 shuttle-supporting surfaces of said upper and lower boxes are inclined rearwardly upward and rearwardly downward with respect to a tangent to the path of swinging movement of the boxes and corresponding substantially to the angles of the warp threads in the adjacent open sheds when the lay and boxes are at back center. 120

4. In a double shuttle loom, a pair of superposed shuttle boxes in which the lower box is provided with upper and lower shut- 125

tle-engaging surfaces inclined rearwardly upward and rearwardly downward with respect to a tangent to the path of swinging movement of the boxes, such inclinations corresponding to the cross section of the shuttle to be received in the lower box and 70 corresponding substantially to the angles of the warp threads in the lower open shed when the the lay and boxes are at back center. 75

In testimony whereof I have hereunto affixed my signature. 80
